UNITED STATES PATENT OFFICE.

J. L. RUNK, OF NASHVILLE, ILLINOIS.

IMPROVEMENT IN GANG-PLOWS.

Specification forming part of Letters Patent No. 41,643, dated February 16, 1864.

To all whom it may concern:

Be it known that I, J. L. RUNK, of Nashville, county of Washington, State of Illinois, have invented a new and Improved Gang-Plow; and I do hereby declare that the following is a full, clear, and exact description thereof, reference being had to the accompanying drawings, making a part of this specification, in which—

Figure 1 is a side elevation with a portion of the axle-tree and hounds removed. Fig. 2 is a top view of the machine complete. Fig. 3 shows the mode of attaching the hounds and seat-supporting bars to the axle-tree, so that the former are capable of being adjusted laterally. Fig. 4 shows in detail the mode of adjusting the plow-beams. Figs. 5 and 6 are two views showing the standard-boxes which receive the standards of the plows.

Similar letters of reference indicate corresponding parts in the several figures.

This invention relates to improvements in that class of plows which have their beams supported by the axle of carriage-wheels, and which require to be lifted free from the ground at every turn in the field, and also in transporting the machine from one place to another.

The object of my invention is to apply leverage to the plow-frame in such manner that the plowman, who is also the driver, can raise or depress his plows with less labor than hitherto.

It also has for its object the more firm attachment of the plows to the swinging beams thereof, at the same time providing for the vertical adjustment of the plows and for regulating the pitch of their points, while their standards are secured to their beams.

It also has for its object the construction and application of the frame of the machine to an extensible axle-tree in such manner that the plows can be adjusted laterally with respect to the furrow-wheel for running into the land at any required distance, all as will be hereinafter described.

To enable others skilled in the art to make and use my invention, I will proceed to describe its construction and operation.

The two carriage-wheels A A' are placed on an axle-tree, B, which consists of a long slotted piece, a, and a short piece, b, which is se-

cured on top of the former by means of a clip, b', and also the screw-bolts which secure the hounds to the axle-tree. This short portion b of the axle carries on its outer end the land-wheel A', or that wheel which runs on the un-plowed ground, while the opposite end of the axle—the portion a—carries the wheel which runs in the furrows or over the plowed ground.

The hounds C are secured at their rear forked ends to the top of the axle-tree portion a by means of screw-bolts d d, which pass upward through oblong slots d', made through the portion a, and enter the hounds C, as shown in Fig. 3, and as the inner end of the short portion b of the axle is mortised into one fork of the hounds the screw-bolts d d secure this piece b, together with the hounds, to the axle-tree portion a. The two forward or contracted ends of the hounds C are secured rigidly to the draft-pole C', the rear end of which extends back beyond the point of its connection with the hounds, for the purpose of receiving a transverse rod, e, which forms a pivot attachment of the forward ends of the parallel plow-beams D D' with the hounds and draft-pole, as shown in Figs. 1 and 2.

Between the pivoted plow beams D D', which extend over the axle and some distance in rear thereof, I have erected a standard, E, upon the upper end of which the spring f, which supports the driver's seat, is rigidly secured. This standard is secured in a perpendicular position to the axle-tree portion a by means of a screw-bolt, g, which passes upward into tenon-projections of the standard E. The tenons on this standard E enter an oblong longitudinal slot, g', for the purpose of allowing this standard to be adjusted laterally when the hounds and short piece b are adjusted. The standard E is slotted or bifurcated at its upper and lower ends, and within these vertical openings pulleys or grooved rollers h h' are pivoted. These pulleys h h' receive around them an endless chain, i, which is attached in any suitable manner in rear of the standard E to the pivoted plow-beams D D'. The chain i is again attached to a lever, G, which is pivoted to the axle of the lower pulley, h'. This lever extends upward in front of standard E to a convenient point for the driver, who sits in seat f', to operate upon it. Lever G is allowed to have a

lateral play sufficient to disengage a pin, *j*, from holes which are made through a curved bar, *H*, which is used for the purpose of receiving pin *j* and holding lever *G* at any desired point. A spring, *k*, on lever *G* presses against a curved guard on bar *H* and keeps the pin *j* in and lever *G* in place, except when it is desired to raise or depress the rear end of the plow-beams, when this spring *k* will yield and allow the driver to adjust the lever *G*. By this arrangement and combination of pulleys and a lever with an endless chain I obtain a great leverage for raising the plows from the ground and enable the driver to effect this operation with very little expenditure of force.

The endless chain *i*, which is attached respectively to the plow-beams *D D'* and to the lever *G*, serves to divide the weight of the plow-beams and plows on each side of the pulleys, and by making this chain of sufficient length it will not interfere with the rising and falling motions of the plows when the machine is in operation.

The semi-elliptical spring which supports the driver's seat is applied to the upper end of the standard *E*, so that the weight (or center of gravity) will fall behind the axle-tree *B*, and thus relieve the horses from the weight of the forward part of the machine, and also that of the driver.

In Figs. 5 and 6 I have shown in detail a new form of box for receiving the standards *m* of the plows *J K*. These boxes *N* are cast with a vertical opening through them for the reception of the plow-standards. The lower opening in the more solid portion of the box is made somewhat smaller in width than the upper opening, and both openings should be made of sufficient width to allow the standard *m* a slight play, as will be further explained. These boxes consist of a lower solid portion, *n*, through which bolts are passed that secure the boxes to the beams *D D'*, and an open contracted portion, *n'*, which is formed with a view to combine the greatest strength with lightness, and which projects above the upper surface of the plow-beams. These boxes may be cast in one solid piece, or they may be cast in parts and bolted together. The plow-standards *m* are secured to the boxes *N* by means of a screw at *o*, which forms a pivot-connection, and also by means of wedges *p p*, which are driven down between the forks and the edges of the standard at the upper end of the boxes, as shown in Figs. 1 and 5. By means of these wedges *p p* the standards can be rigidly fixed in position, and by means of the screw or pivot *o*, together with the wedges *p p*, the standard can be inclined and the point of the plow given any desired pitch, and the whole secured rigidly in the desired position. For this purpose one of the wedges is driven down until the desired pitch has been obtained, when the other wedge is driven in place. By removing the

wedges and loosening the screw *o* the standards can be adjusted vertically and again fixed in place, as above described. By means of boxes constructed as described I obtain two points of support for the plow-standards, and am also enabled to incline the standards for regulating the pitch of the plow-point without loosening the pivot-screw *o*. I also obtain a more firm attachment of the plows to their beams than hitherto. One of the boxes, *N'*, is applied to the beam *D'* near its rear end, while the other box, *N*, is applied to the opposite beam, *D*, in advance of box *N'*, as shown in Fig. 2. These two standard-boxes are for the purpose of receiving the standards of the heavy breaking-plows; but in conjunction with these boxes I have applied a supplemental box, *P*, to beam *D*, in rear of the box *N*, for the purpose of receiving the standard of a subsoil-plow, *K*, which it is desired to employ in connection with the forward breaking-plow. By means of this box *P*, applied as described in rear of the foremost box, *N*, I am enabled to use an auxiliary plow for stirring and turning up the subsoil when it is desired to plow very deep, or deeper than can be practically done with the large breaking-plow.

It will be obvious that instead of wedge-fastenings screws may be used for adjusting the upper ends of the plow-beams. Two screws would be used for each standard-box, or one set-screw and one wedge.

Having described my invention, what I claim is—

1. The combination of the pulleys *h h'*, endless chain *i*, and adjusting-lever *G* with pivoted plow-beams *D D'*, attached to the tongue *C'* in front of the axle-tree, all operating substantially as described.
2. The manner herein described of uniting the two parts of the axle and the hounds, so that when the axle is extended in length or shortened the hounds will be adjusted to operate therewith, as set forth.
3. The laterally-adjustable pulley-standard *E*, in combination with the laterally-adjustable hounds *C*, plow-beams *D D'*, and extensible axle-tree *B*, substantially as described.
4. The combination of the pivoted plow-beams *D*, extensible axle-tree *B*, and laterally-adjustable hounds *C*, in the manner and for the purpose specified.
5. The specified construction of standard-boxes *N*, so that they afford two bearings or supports, *n n'*, while made in one piece, *N*, and otherwise operate with wedges or set-screws, for the purpose set forth.
